(57) **CLAIM**

The ornamental design for a brochure stand, as shown and described.

DESCRIPTION

FIG. 1 is a front elevational view of a brochure stand, showing my new design in a folded position;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front perspective view thereof, from above;

FIG. 8 is a front perspective view thereof, from below;

FIG. 9 is a rear perspective view thereof, from above;

FIG. 10 is a rear perspective view thereof, from below;

FIG. 11 is a front elevational view, similar to FIG. 1, but showing my new design in an opened or unfolded position;

FIG. 12 is a rear elevational view thereof;

FIG. 13 is a top plan view thereof;

FIG. 14 is a bottom plan view thereof;

FIG. 15 is a left side elevational view thereof;

FIG. 16 is a right side elevational view thereof;

FIG. 17 is a front perspective view thereof, from above;

FIG. 18 is a front perspective view thereof, from below;

FIG. 19 is a rear perspective view thereof, from above; and,

FIG. 20 is a rear perspective view thereof, from below.
